(57) **CLAIM**

The ornamental design for an open-sided pinch bag, as shown and described.

DESCRIPTION

FIG. 1 is a left side elevational view of a open-sided pinch bag.

FIG. 2 is a right side elevational view thereof.

FIG. 3 is a top plan view thereof.

FIG. 4 is a front elevational view thereof.

FIG. 5 is a rear elevational view thereof.

FIG. 6 is a front right perspective view thereof.

FIG. 7 is a front left perspective view thereof.

FIG. 8 is a front right perspective view showing the nature and environmental use thereof as a open-sided pinch bag.

FIG. 9 is a left side elevational view of a open-sided pinch bag.

FIG. 10 is a right side elevational view thereof.

FIG. 11 is a top plan view thereof.

FIG. 12 is a front elevational view thereof.

FIG. 13 is a rear elevational view thereof.

FIG. 14 is a front right perspective view thereof.

FIG. 15 is a front left perspective view thereof.

FIG. 16 is a front right perspective view showing the nature and environmental use thereof as a open-sided pinch bag.

FIG. 17 is a left side elevational view of a open-sided pinch bag.

FIG. 18 is a right side elevational view thereof.

FIG. 19 is a top plan view thereof.

FIG. 20 is a front elevational view thereof.

FIG. 21 is a rear elevational view thereof.

FIG. 22 is a front right perspective view thereof.

FIG. 23 is a front left perspective view thereof.

FIG. 24 is a front right perspective view showing the nature and environmental use thereof as a open-sided pinch bag.

FIG. 25 is a left side elevational view of a open-sided pinch bag.

FIG. 26 is a right side elevational view thereof.

FIG. 27 is a top plan view thereof.

FIG. 28 is a front elevational view thereof.

FIG. 29 is a rear elevational view thereof.

FIG. 30 is a front right perspective view thereof.

FIG. 31 is a front left perspective view thereof; and,

FIG. 32 is a front right perspective view showing the nature and environmental use thereof as a open-sided pinch bag. FIGS. 1-8 and 17-24 depict the ornamental design of the open-sided pinch bag having a bottom fold on the left side when viewed straight on from the open end, and FIGS. 9-16 and 25-32 depict an alternative design where the bottom fold is on the right side when viewed straight on from the open end. Applicant believes these embodiments are patentably indistinct, thus requiring a single claim.

The bottom surface of the open pinch bag is unornamented.

(Continued)

The broken lines in the drawings represent visible environmental structure that form no part of the claimed design.
